UNITED STATES PATENT OFFICE.

JOHN A. FERRIS, OF CHICAGO, ILLINOIS.

WATER-HEATER.

1,211,927.

Specification of Letters Patent.

Patented Jan. 9, 1917.

Application filed February 10, 1916. Serial No. 77,402.

To all whom it may concern:

Be it known that I, JOHN ARTHUR FERRIS, a citizen of the United States, residing at Chicago, in the county of Cook and State 5 of Illinois, have invented a new and useful Water-Heater, of which the following is a specification.

My invention relates to a water heater for household or domestic service, and my improvements consist in a novel method of 10 construction, and means of causing a rapid increase in the temperature of the water held by the pipe coils and in the water bowl of the said water heater.

15 Figure 1, shows an interior view of my improved water heater. Fig. 2, shows a plan view of different parts taken beneath the line y, z , of Fig. 1. Fig. 3, shows a plan view taken beneath the line x, g , of 20 Fig. 1. Figs. 4 and 5 are detail views of the bush-cap that connects the upper ends of the pipe coils to the water bowl of the water heater.

Similar letters of reference refer to similar parts throughout the several views.

The outer casing B of the water heater is of sheet metal preferably of a cylindrical form and near the lower end of the said casing is located a perforated plate b , 25 of sheet metal. Resting upon the perforated plate b , is shown an electric stove C. Immediately above the stove C is located several pipe coils 1, 2, 3, and the upper ends of the said pipe coils connect with the bottom 30 of the water bowl D, centrally suspended within the casing B. The bottom of the bowl D is upset, so as to form several semi-spherical protuberances d , projecting inward, and at the center of the bottom 35 of the bowl is a similar protuberance d' projecting downward for connection with a bush-cap 4 attached to the pipe coils. The lower ends of the pipe coils 1, 2, 3, also connect with a bush-cap 5 connected 40 to the faucet G, so that water can be withdrawn from the pipe coils 1, 2, 3, and the bowl D connected with the said pipe coils.

Surrounding the pipe coils 1, 2, 3, and the electric stove C is a conical sheet metal 45 jacket F, and joining with the contracted end of the jacket F is a cup shaped disk f of sheet metal, of a diameter equal to the inner diameter of the casing B. The conical sheet metal jacket F is surrounded with 50 sheet asbestos h or other suitable material to prevent outwardly heat radiation through

the sheet metal jacket. The cup shaped disk f is also surrounded with a jacket of sheet asbestos h' for a similar purpose. The sheet metal conical jacket F is inclined inwardly at the top, so as to concentrate the heated air ascending from the electric stove C upon the spiral pipe coils 1, 2, 3, and also to centrally focus the heated air upon the bottom of the bowl D, previous to the 60 heated air surrounding the shell, of the bowl D. The stove C, as represented in the drawings, is of an electric type, and a gas or oil stove can be used with similar results, in connection with the water heater. 70

The object of the apparatus is the rapid and economical heating of the water in the pipe coils 1, 2, 3, and in the bowl D. The heated air ascending from the stove C is deflected in its ascent by the sheet metal 75 jacket F upon the pipe coils and subsequently concentrated toward the center of the bottom of the bowl D, previous to the heated air surrounding the cylindrical shell of the bowl. The cold air supporting combustion enters through the perforated plate b , as indicated by the lower arrows, and becoming heated circulates naturally first 80 around the pipe coils 1, 2, 3, and ascends and impacts against the bottom of the bowl D, 85 and subsequently surrounds the circular shell of the said bowl, so that the heat of the heated air ascending from the electric stove C, is rapidly absorbed by the water within the pipe coils, 1, 2, 3, and the water 90 within the bowl D, and a high efficiency of the heat attained that is developed by the electric stove C, in heating the water within the pipe coils 1, 2, 3, and in the water bowl D. The semi-spherical protuberances upon the bottom of the bowl D, 95 is a means of increasing the area of the bottom of the bowl D, and is also a means of causing a corresponding heat radiation through the bottom of the bowl D. 100

Having described the several parts of my invention and its operation, what I claim as new and desire to secure by Letters Patent is as follows:

In a water heater the combination of a 105 stove C within a casing B a water bowl D provided with a bottom formed with several semispherical depressions d, d' , and the said bowl depending within the said casing, conical spiral pipe coils located between the 110 stove C and the water bowl with the upper ends of the said pipe coils joined to the

bottom portion of the water bowl, a faucet G communicating with spiral pipe coils by a connecting bush cap, a conical sheet metal jacket F surrounding the spiral pipe coils, 5 a cup shaped metal disk above the conical jacket and joining thereto, and sheet asbestos outwardly covering the said conical jacket and the cup shaped metal disk, to prevent heat radiation through the conical

jacket and the metal disk supported thereby, substantially as described and shown.

In testimony whereof I have signed my name to this specification.

J. A. FERRIS.
